UNITED STATES PATENT OFFICE.

ROBERT STICKDORN, OF DUSSELDORF, GERMANY.

CLOSET-FLUSHING APPARATUS.

No. 880,594.

Specification of Letters Patent.

Patented March 3, 1908.

Application filed December 5, 1906. Serial No. 346,379.

To all whom it may concern:

Be it known that I, ROBERT STICKDORN, a subject of the German Emperor, residing at Dusseldorf, Germany, have invented new and useful Improvements in Closet-Flushing Apparatus, of which the following is a specification.

The object of the present invention is to provide a closet flushing apparatus which is fitted with a differential piston and a water reservoir which, by pulling a lever or a chain, or other similar means, is filled and emptied again without further manipulation, the reservoir remaining empty until the basin again requires flushing.

The invention has special relation to an arrangement which effects, after the raising of the differential piston as a consequence of the release by hand of the water under the large piston, not only the filling of the specially shaped tank, but also a renewed feed of water under the large piston, which causes the automatic opening of the flush-pipe valve after the replenishing of the tank. By means of a further arrangement the alternate automatic filling and emptying of the basin or reservoir is obtained.

In the accompanying drawings: Figure 1 is a vertical section, partly in elevation, of my improved closet flushing apparatus; Fig. 2 a similar section, partly broken away, of a modification thereof; Fig. 3 an elevation, partly broken away, of the apparatus shown in Fig. 1, and Fig. 4 a cross section on line X—X, Fig. 3.

The mechanism of the apparatus is inclosed in a housing 1, with which the reservoir 2 and the flush-pipe 3 are connected and to which are attached the cylinders 4 and 5 for the differential piston. The small cylinder 5 is connected with the pressure feed-pipe 6 by a bend 7 and with the reservoir 2 by an opening 8, while the large cylinder 4 is connected through passage 9 with a cylinder 10. In the latter is inclosed the piston 11 which is raised by means of the lever 12 when it is required to release the water under the cylinder 13 of the differential piston and to fill the reservoir 2, and which, as soon as the same is filled, is depressed by the water pressure.

When the piston 11 is raised, the water under the large piston 13 flows through the passage 9 into the cylinder 10 of the housing 1, and through ports 15 and 16 into the flush-pipe 3.

The operation is as follows: The piston 13,

which is freed by the pressure, is depressed, together with the small piston 14, by the pressure on the latter, so that the valve 17 connected with the piston is depressed and closes the flush-pipe 3. The reservoir is now filled through the inlet 8 which connects it with the interior of the small cylinder 5 and which is placed well towards the lower end of the latter. In order to retard, in some measure, the flow of the water into the basin or reservoir so that the pistons 13, 14 are safely kept depressed, there is a bored cap 18, over the opening 8. When the filling is completed, pressure is caused in the air-tight tank, so that the water cannot continue to flow, and in consequence exercises its pressure on the small piston 11, previously raised by the lever 12, and again depresses it. The result of this movement of piston 11, is that the ports 15 and 16 are closed and that water from the cylinder 10 is forced through the passage 9 under the large piston 13 and that the two pistons 13 and 14 are raised to thereby open valve 17, (Fig. 1). The water can then flow out of the tank for flushing the basin, while the entry of the water to the tank is closed as pipe 7 is closed. The valve 17 which closes the flush-pipe at the bottom, is connected with the pistons 13, 14 by a spindle 29 in such a manner that the valve is not raised till the pistons rise sufficiently to prevent the entry of any water through the openings 8.

In order to attain an automatic alternate filling and emptying of the reservoir 2, the arrangement shown in Fig. 2, may be adopted. The piston 11 is so arranged that it is actuated by the pistons 13, 14. On the piston 14 there is a rod 19 which carries an arm 20 which engages with a rod 21 of piston 11. When the pistons 13, 14, and the valve 17 are raised on the escape being opened, the piston 11 is also raised by the arm 20 striking a block 22 on the rod 21, so that the water under the large piston 13 can escape. As a consequence, the pistons 13, 14, and the valve 17 fall and the reservoir is again filled, the resulting pressure finally driving the valve or piston 11 down to free the opening 9, so that the water can flow under the piston 13 and lift it again and open the flush-pipe. In order that no resistance (air or water) is offered to the upward movement of the pistons 13 and 14, spindle 29 is perforated as at 30.

At the top of reservoir 2, is arranged a separate reservoir 23 for a disinfectant, from which there is always a certain quantity

drawn on the flush taking place. To this effect rod 19 is provided with a piston 27 working in a cylinder 25 that communicates with reservoir 23. On the fall of the pistons 5 13 and 14, this motion is communicated to piston 27, so that a small quantity of the disinfectant is drawn through the opening 26 into the cylinder 25, (Fig. 2). When the piston is again raised, (Fig. 1), the outlet 26 is 10 closed, while the disinfectant is forced through outlet 28 into the reservoir 2 and mixed with the water.

I claim:

In a flushing apparatus, a water tank, combined with a first cylinder communicating therewith, a second cylinder, a differential piston engaging both cylinders, a flush pipe, 15

a valve on the piston controlling communication between the tank and the flush pipe, a water inlet pipe communicating with the first cylinder above the piston, a passage connecting said inlet pipe with the second cylinder below the piston, a valve operable by the tank-pressure and controlling communication between said passage and the water inlet 20 pipe and also between said passage and the flush pipe, substantially as specified.

Signed by me at Dusseldorf, Germany this seventeenth day of November, 1906.

ROBERT STICKDORN.
